UNITED STATES PATENT OFFICE.

SIGARD A. S. HAMMAR, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

BREECH MECHANISM.

SPECIFICATION forming part of Letters Patent No. 795,221, dated July 18, 1905.

Application filed July 16, 1901. Serial No. 68,523.

To all whom it may concern:

Be it known that I, SIGARD A. S. HAMMAR, a subject of the King of Sweden and Norway, residing at Bethlehem, in the county of Northampton and State of Pennsylvania, have invented certain new and useful Improvements in Breech Mechanism, of which the following is a specification.

My invention relates to the breech mechanism of guns; and it consists in the construction of the firing mechanism and in the means for supporting and operating the same and for securing the breech-block, as fully set forth hereinafter and as shown in the accompanying drawings, in which—

Figure 1 is a sectional plan of the breech of a gun provided with my improvements. Fig. 2 is a rear elevation; Fig. 3, a detached sectional view of the support for the firing mechanism; Fig. 4, a detached view of a detent; Fig. 5, a detached plan of the breech-block; Fig. 6, a detached view of the firing-pin. Fig. 7 is a perspective of the sleeve of the detent detached.

Upon the breech-block carrier of the gun is secured a support which carries the entire firing-gear and is connected to and may, if desired, be integral with the carrier. Preferably, however, it is detachable therefrom. The hub of the support also supports the breech-block. As shown, the support consists of a hub 1 and a block 2, and the block 2 lies against the outside of the breech-block carrier 3, the hub projecting through a threaded recess or opening *x* in the carrier and being introduced therein by screwing until the face of the block 2 bears against the rear face of the carrier. The exterior of the hub 1 has threads 4 adapted to threads in the socket of the breech-block 5, as well as to those in the opening in the carrier. It will be understood, however, that the hub may extend through an opening in the carrier without being screwed thereto, the block being bolted or otherwise fastened to the carrier.

While the firing-gear may be of any suitable construction, I prefer to make the same

so that the entire firing mechanism may be carried by the hub 1 to be retained in connection therewith when the hub is withdrawn, so that such withdrawal is not accompanied in any way with the disconnection of any parts of the firing-gear from the hub itself while exposing the same to view for inspection or manipulation, as desired.

The hub 1 and block 2 are socketed for the reception of the firing-pin 6, between the shoulder 7 of which and a shoulder 8 of the hub is interposed the firing-spring 9. The firing-pin slides in a socket in the block 2 and projects to the rear and is provided with an eye *y*, through which the finger may be passed for cocking. The block 2 has a recess *w* for receiving the locking device or detent which holds the firing-pin in its cocked position. This detent may be of different constructions, but as shown it consists of a hollow sleeve 10, sliding in the recess *w* and moved inward under the action of a spring 12, bearing against one end of the recess *w*. In connection with the sleeve, which constitutes a part of the sear, is an L-shaped member *a*, Fig. 4, the shank 14 of which extends through the sleeve 10, while the arm 15 extends into a slot *u* cut in one side of the hub 1. The end of the shank 14 of the detent extends through an opening in the block 2 and is provided with an eye *t*, to which the lanyard may be attached. The inner end of the sleeve 10 is forked or provided with lugs 39, Fig. 7, adapted to extend on opposite sides of the firing-pin, so that when the firing-pin is retracted the lugs engage shoulders 40 thereon and the only means for retracting the sleeve to release the firing-pin is the withdrawal of the member *a*. This can only be effected when the arm 15 is opposite slots *m* *x* in the breech-block and the block-carrier 3. The arm 15 is always opposite the slot *x* in the carrier, but is only opposite the slot *m* in the breech-block when the latter has been turned home to its proper position for firing, when the two slots will coincide and the member *a* may be drawn out, the arm 15 passing into the slots and the end of the sleeve 10 passing away from the

shoulders *s* of the firing-pin, releasing the latter and allowing it to move inward under the action of the spring *9*. When the arm *15* enters the slot *m*, it prevents further rotation of 5 the breech-block.

In many instances it is desirable to release the detent by means of a lanyard passing forward to the side of the gun instead of extending directly laterally or to the rear. To 10 permit this to be done, I combine with the detent an actuating device of any suitable character, the movement of which will retract the detent and release the firing-pin, and with 15 this device I connect an arm *17* at such an angle that the lanyard may extend forward therefrom. If desired, this arm may be arranged so as to clear the other parts, as shown in dotted lines, Fig. 2, or it may be in a lower position, (shown in full lines,) in which case there 20 is a channel or opening *19*, made in the hinge of the carrier for the forward passage of the lanyard. It will be obvious that this arm may be arranged below instead of above the firing-pin.

25 In many instances it is desirable to cock the firing-pin automatically, and I therefore provide the following means for securing this result, (see Figs. 5 and 6:) Upon the rear end of the breech-block is a slope *30* and upon the 30 firing-pin, Fig. 6, is an arm having a bearing end or shoulder *31*, against which as the breech-block is turned is brought the face of the said slope, whereby the continued rotation will force back the firing-pin until it is secured by the detent. The breech-block is also secured by a latch *b*, which is provided with guide-ribs *33*, adapted to grooves in the carrier *3*, permitting the latch to slide at right angles or radially to the axis of the breech-block and carrier, being thrown inward by a spring *34*. From the outer end of the latch extends diagonally the finger *35*, adapted to an angular slot or recess *36* in the breech. As the carrier is moved toward the breech 45 the end of the finger *35* enters the recess, and the continued pressure of the carrier toward the breech, bringing the inclined faces of the finger and recess together, results in forcing the finger outward and fully into the recess, as shown in Fig. 1. The breech-block in firing position prevents the inward movement of the latch *b*, but in the rear of the breech-block is a recess *z*, Fig. 2, which when the breech-block is turned so as to be in position 50 for withdrawal from the breech is opposite the inner end of the latch *b*, which is moved into such recess *z* as the carrier is swung away, the breech-block being thereby locked in its proper position in the carrier *3* and held in 55 that position until the breech is again closed, when the latch will be automatically carried to the position shown in Fig. 1 and withdrawn from the recess *z*, permitting the breech-block to be again turned to its firing 60 position. Whether the breech be closed or

open the support can be detached from the carrier by simply rotating the same to withdraw it from the socket in the carrier, when all of the parts of the firing-gear will be detached from the gun and will be maintained 70 in position for inspection, adjustment, or repair, and without any opportunity for the loss of any loose or detached pieces. The socket which receives the finger *35* of the latch is provided with a detachable cover *37*, secured 75 by one or more bolts *38* or otherwise and which practically constitutes the outer wall of the socket receiving the finger *35*, so that by detaching the cover there is no obstacle to the outward movement of the said finger to 80 permit the carrier to be swung away when this becomes necessary without turning the breech-block. This assumes the support to have been withdrawn.

It will be evident that the sliding sleeve 85 acting as a sear to hold the firing-pin in its retracted position, may be used in connection with other forms of firing mechanism than the form herein shown, as also may some of the other parts of the construction. It will 90 be seen that the use of such a sear, which may be in the form of any part independent of the lanyard-stem, insures the locking of the firing-pin independent of any action of the lanyard-operating stem, so that the tampering with 95 the latter will have no effect in releasing the firing mechanism until all of the parts are in such position that the said stem can be properly manipulated.

By making the device in two parts it will 100 be seen that there can be no possible release of the firing mechanism during the opening and closing of the gun. When the firing-pin is drawn back, lugs *40* thereon come against inclines *41* on the lugs *39* of the sleeve *10* and force the sleeve back until the lugs *39* pass in front of the shoulders *40*.

Any suitable means may be employed for 105 turning the breech-block on the hub—as, for instance, a lever *M* and link *N*, (not herein claimed,) the threads on the hub and breech-block being at the proper angle to give the breech-block the desired longitudinal motion in locking and unlocking the breech.

Without limiting myself to the construction 110 of parts shown, I claim—

1. The combination with the breech-block and the breech-block carrier, of a support provided with a hub adapted to pass through a recess in the carrier and into the breech-block 115 and to support said block and the entire firing-gear, and means for securing the parts in position, substantially as set forth.

2. The combination with the carrier having a threaded opening therein, of a support for the firing mechanism having a threaded hub adapted to said opening, and a breech-block having a threaded socket adapted to said hub, the threads of the breech-block and hub being 120 at the proper angle to give the breech-block 125

the desired motion to the rear or forward in unlocking and locking the breech, substantially as set forth.

3. The combination with the carrier having a threaded opening therein, of a support provided with a threaded hub adapted to said opening, a breech-block having a threaded socket adapted to said support, the threads of the breech-block and hub being at the proper angle to give the block the desired motion in locking and unlocking the breech, and a firing-gear carried entirely by said support, substantially as set forth.

4. The combination with the rotatable breech-block, the carrier therefor, and the support provided with a hub adapted to pass through the carrier and into the breech-block to support the latter, of a firing-pin, its spring, a movable member having an arm, and a detent movable with said arm, the breech-block and the carrier having recesses which must be brought into proper relative position to receive said arm to permit the withdrawal of the detent, substantially as described.

5. The combination with the carrier, and the rotatable breech-block, each having a recess, of a firing-pin, a detent, a movable member having a laterally-projecting arm adapted to enter said recesses when the breech-block is in firing position, the detent adapted to engage and lock the firing-pin in its cocked position and to be disengaged therefrom by the movement of said arm, substantially as set forth.

6. The combination with the rotatable breech-block, and the carrier therefor, of a

support provided with a hub having a recess in one side and adapted to pass through the carrier into the breech-block to support the latter, a firing-pin in the hub, a detent in the support, and a movable member having a laterally-projecting arm adapted to occupy the recess in the hub and to prevent the movable member from being shifted to move the detent to release the pin when the breech-block is out of firing position while allowing the independent outward movement of the detent in cocking the pin, substantially as set forth.

7. The combination with the firing-pin, having shoulders 40, and the sliding sear adapted to engage said shoulders, of the shank 14 sliding within said sear and provided with a projecting arm, and a rotating breech-block provided with a recess for receiving said arm when the parts are in position for firing, substantially as described.

8. The combination of the carrier, the rotatable breech-block having an inclined bearing on its rear face, the support having a hub extending through the carrier and into the breech-block to support the latter, a firing-pin provided with a shoulder adapted to engage said bearing, and a detent for holding the pin in its cocked position, substantially as set forth.

In testimony whereof I have signed my name to this specification in the presence of two subscribing witnesses.

SIGARD A. S. HAMMAR.
